DISCONNECTING SWITCH

Peder B. Hoye, Maywood, Ill., assignor to Electrical Engineers Equipment Co., Melrose Park, Ill., a corporation of Illinois

Application May 17, 1955, Serial No. 516,670

6 Claims. (Cl. 200—48)

The present invention relates to disconnecting switches for high tension electrical power installations, particularly to air break switches of the type having a switch blade movable in an arc and rotatable about its own axis, and to improved operating means for such switches.

Air break switches of the character referred to are normally intended for outdoor installation, and in northern climates are therefore subject to icing conditions. Accordingly, it is essential that the switch be capable of freeing itself of ice and like obstructions if the switch is to be practical. One type of switch widely employed in the art affords a particularly efficient solution to the problem by imparting to the switch blade the characteristic movement of rotation within the switch contact and arcuate movement toward and away from the contact to close and open the switch. Assuming the switch to be closed, the same is opened by first imparting to the blade a predominantly rotary movement within the contact to shear any ice and free the blade end from the contact, whereafter the blade is moved arcuately out of the contact to open the switch. On closing of the switch, reverse operation occurs, i. e., the blade end is moved arcuately into the contact and then rotated into contact engagement. Because of this particular operation, the switch further affords the distinct advantage of facilitating ready insertion of the blade end into and ready removal of the blade end from the contact substantially without contact pressure thereon, and yet affords an optimum high pressure small area engagement of the blade with the contact in switch closed position. This is accomplished by flattening the blade end or forming the same of beaver tail configuration to cooperate with a generally U-shaped contact having parallel legs or leaves. The beaver tail at the blade end has a minor dimension freely insertable between the legs of the contact and a major dimension that is greater than the normal spacing between the legs of the contact. The operating mechanism of the switch is so constructed and arranged that the blade end is moved into the contact at least with the beaver tail inclined to the legs of the contact to accommodate ready insertion of the blade end into the contact. Subsequently, the operating mechanism rotates the blade to dispose the major dimension of the beaver tail blade end transversely of the contact leaves or legs, thus to force the blade into high pressure small area engagement with the contact. On switch opening movement, the operating mechanism first rotates the blade to free the blade end from the high pressure engagement and thereafter moves the blade arcuately out of the contact.

In an early development of switches of this character, the operating means or mechanism effected the above described rotary and arcuate movements of the blade successively, but independently, so that blade rotation was effected entirely before removal of the blade end from the contact, or entirely after entry of the blade end into the contact. This switch afforded the advantages of high pressure, small area contact and ice breaking on switch opening movement, but suffered the particular disad-

2

vantage that it was not fully controlled, i. e., on closing movement of the blade, if the contact were obstructed (such as by ice in an outdoor installation), the switch blade could not be forced down through the obstruction by the operating means, but instead, the operating means could rotate the blade to complete blade movement even though the blade end were not in the contact.

A further development in the art afforded blade control in the region of the switch contact both in the opening and closing directions. This switch is characterized by operating means for effecting simultaneous rotation and arcuate swinging of the blade, which means comprises, in terms of a conventional horizontal switch installation, a frame defining a horizontal pivot axis, a blade guide or hinge pivotally mounted on the frame, a blade carriage to which the blade is secured rotatably in the blade guide or hinge about an axis at right angles to the horizontal pivot axis, an operating crank rotatable about a vertical axis, and pivot means between the crank and blade carriage, the pivot means in the specific embodiment being disposed with its axis at 45° to the horizontal and vertical, and the operating means being further characterized by intersection of the horizontal pivot axis of the blade guide or hinge, the axis of the blade, the vertical axis of rotation of the crank and the axis of the pivot means in a common point. The switch as thus constructed affords particular advantages over the earlier development in the art in terms of blade control, for the blade in this switch is positively forced or driven downwardly into the contact on switch closing movement, and positively removed from the contact on switch opening movement. The rotary movement of the blade, while occurring simultaneously with the arcuate movement thereof, predominates in the region of the contact so that the beaver tail blade end is readily inserted into and removed from the contact and is rotated an adequate extent within the contact to attain the previously described high pressure small area contact, and the desired ice breaking functions at the switch contact both upon opening and closing movements of the switch blade. This switch has proven highly successful in use and has been widely adopted. However, the switch does suffer the disadvantage that it is not fully controlled throughout the full range of movement thereof. Specifically, in the full open position of the switch blade, the blade extends vertically upward in axial alignment with the axis of rotation of the operating crank so that the operating mechanism is disposed on dead center. Rotation of the operating crank to actuate the 45° pivot means can result in no more than rotation of the blade. This dead center position is also completely or partially reached in modifications of the described switch operating mechanism attaining or approximating the axial alignment of the blade and crank axes in switch open position. To avoid the consequences of the defined dead center position, the said operating mechanism and most modifications thereof must include specially provided kicker means or reaction means to move the switch blade out of its dead center position, and even with such means it is apparent that control of the blade becomes increasingly less as the blade approaches or approximates dead center position.

It is the object of the present invention to overcome the described disadvantages of prior developments in the art and to afford a switch of the character defined including a switch blade that is fully controlled throughout the complete range of movement thereof.

More particularly, it is an object of the present invention to provide improved operating means or mechanism for switches of the character defined, which operating means or mechanism by itself exerts full control over the blade in all positions of the blade.

Another object of the invention is to provide improved operating mechanism for switches of the character defined affording novel interrelation of a switch blade, a blade guide or hinge, an operating crank and pivot means between the blade and crank whereby the axis of the blade does not coincide, align, or substantially align with the axis of rotation of the operating crank in any position of the blade, and, by this interrelation, affording at all times an effective lever arm between the blade and crank to maintain full control over the blade from the crank without the intervention of previously required kicker or reaction means.

A further object of the invention is the provision of improved operating mechanism for switches of the character defined, particularly of the type wherein the switch blade is swung in an arc and simultaneously rotated, affording, in addition to the advantages above described, improved operational characteristics in terms of increased blade rotation in proportion to arcuate movement of the blade during the initial and final stages, respectively, of switch opening and switch closing movements, thus to enhance and improve upon the previously defined basic operational characteristics of the described type of switch.

A still further object of the invention is the provision of an improved air break disconnecting switch of efficient, practical and highly economical construction.

Other objects and advantages of the present invention will become apparent in the following detailed description of preferred embodiments of the invention.

Now, in order to acquaint those skilled in the art with the manner of making and using the improved disconnecting switch of the invention, I shall describe, in connection with the accompanying drawings, preferred embodiments of the invention and preferred manners of making the same.

In the drawings, wherein like reference numerals indicate like parts:

Figure 1 is a side elevation of the improved disconnecting switch of the invention, the view showing the switch blade in closed position in solid lines and in open position in dotted lines;

Figure 2 is a longitudinal vertical section of the improved operating mechanism afforded by the invention;

Figure 3 is a top view, partly in plan and partly in section, of the mechanism shown in Figure 2 omitting the switch blade;

Figure 4 is a front elevation of the operating mechanism;

Figure 5 is a section, taken substantially on line 5—5 of Figure 2, showing the operating crank or lever and indicating the arc of movement thereof;

Figure 6 is a side elevation of a modification of the operating mechanism shown in Figure 2 adapted particularly for higher capacity installations; and

Figure 7 is a graph showing the relation between blade rotation and arcuate movement as imparted to the blade by the operating mechanism of the invention.

Referring now to the drawings, and particularly to Figure 1, the switch of the invention is shown in a conventional horizontal installation as including a rigid base 10 to be mounted horizontally or vertically, and a first insulator stack 12 extending perpendicularly from one end of the base and carrying at its outer end a generally U-shaped contact 14. In substantially spaced relation to the insulator stack 12, the base carries a pair of parallel insulator stacks 16 and 18, the outboard one 16 of which is stationary and the inner one 18 of which is rotatably mounted on the base 10. At its outer end, the stack 16 affords a stationary support for an operating means or mechanism, indicated generally at 20, having connection to a switch blade 22 for purposes of simultaneously rotating the blade and moving the same in an arc from the closed position shown in solid lines to the open position shown in dotted lines wherein the switch blade extends outwardly from and generally parallel to the insulator

stack 18. The switch blade is flattened at its outer end to define a relatively thin, broad contact portion 23 adapted for high pressure engagement in the U-shaped contact 14 in the manner and to attain the advantages pointed out hereinbefore. The rotatable insulator stack 18 is operatively connected at its outer end to the means or mechanism 20 to impart to the switch blade 22 the simultaneous movements of rotation and arcuate swinging upon rotation of the stack 18.

The operating means or mechanism 20 is shown in greater detail in Figures 2 to 5 and comprises a frame 30, a blade guide or hinge member 40, a blade carriage or arm member 50, and an operating crank or lever 60. The frame 30 suitably comprises a metallic casting and includes a terminal end portion 31 fixedly secured, as by bolts, to the outer end of the stack 16 and defining a terminal pad 32. Forwardly of the portion 31, the frame is bifurcated or of yoke form to define parallel arms 33 extending upwardly and forwardly to a point above the rotatable stack 18, from whence the arms extend downwardly and inwardly to join integrally in a bearing portion 34 rotatably receiving, in effect, the upper end of the rotatable insulator stack 18 to afford a firm support for both of the stacks 16 and 18 and the frame 30. In the portion thereof outwardly of the stack 18, the arms 33 of the frame 30 are provided with aligned bores within which stub axles 35 are received to define a horizontal pivot axis, generally at a right angle to the axis of rotation of the stack 18.

The blade guide or hinge member 40 may also be a metallic casting and includes a central tubular body portion 41 and a pair of oppositely disposed arms 42 of angle form. The arms 42 extend outwardly and rearwardly from the body 41 to constitute a generally U-shaped clevis, the arms at their outer ends receiving the stub axles 35 pivotally to mount the blade guide or hinge 40 on the frame 30.

The blade carriage or arm member 50, also a metallic casting, includes a tubular body portion 51 having an outer diameter slightly less than the inner diameter of the body portion 41 of the blade hinge 40 and an inner diameter equal approximately to the outer diameter of the switch blade 22. The blade 22 is received in and carried by the body portion 51 of the carriage 50, the carriage being clamped to the blade adjacent but in spaced relation to one end of the blade by means of a bolt 52. The body portion of the carriage, in turn, is rotatably received in the tubular body portion 41 of the blade guide, bearing means being provided to journal the carriage in the guide. To retain the carriage in the guide, the carriage includes a radial flange 54 adjacent one end of the tubular body thereof to engage against one end of the body 41 of the guide or hinge, and at the other end of the hinge, a castellated nut 55 is threaded on an extending end portion of the carriage body. Immediately rearwardly of the tubular body thereof, the carriage 50 includes an operating arm 56 extending downwardly and rearwardly in angular relation to the body of the carriage, approximately at a 45° angle in the embodiments disclosed herein, although the angle is not particularly critical. At its outer or lower end, the arm 56 includes a socket within which is fixed a stem or extension 57, the purpose of which will become apparent as the description proceeds.

The operating crank or lever 60, like the other components of the operating mechanism, preferably comprises a metallic casting. The crank comprises a generally circular body portion 61 which is secured, by bolts or the like, to the upper end of the rotatable insulator stack 18. The body 61 includes a central or axial upwardly projecting extension or stem 62 which is rotatably received in the bearing portion 34 of the frame 30 for the purpose previously pointed out, a roller bearing 63 journaling the stem in the portion 34. To retain the stem in the bearing, a nut 64 is threaded to the upper end of

the stem, and to shield the bearing 63, a washer 65 is disposed over the bearing beneath the nut. The lever arm 66 of the crank extends radially outwardly from the body 61 and at its outer end is turned up at an angle complementary to the angle of the carriage arm 56 to receive the arm or stem 57. Within the angular end portion thereof, the lever or crank arm 66 is recessed and a non-corrosive spherical bearing 67 is mounted in the recess. The bearing 67 rotatably and slidably receives the stem 57 of the carriage arm 56 and due to its mounting couples the arm 56 and crank 60 with accommodation for relative sliding, rotating and swiveling movements. As will be appreciated, if desired, the stem could be fixed to the crank, and the spherical bearing provided in the arm of the blade carriage.

From the foregoing, it is to be appreciated that the operating mechanism as thus far disclosed comprises a stationary frame 30, a blade guide or hinge 40 pivotally mounted on the frame, a blade carriage 50 rotatably mounted on the hinge 40, the carriage 50 carrying the switch blade 22 coaxially and mounting the switch blade for rotation about its own axis, and a rotatable operating crank 60 operatively connected to the carriage 50. With the exception of the association of the crank 60 with the stem 57 of the carriage 50, the elements described and their general association are known in the art, and in the closed position of the switch, as shown in solid lines in Figure 3 and in Figure 1, the pivot axis of the guide or hinge, the axis of rotation of the carriage and blade and the axis of rotation of the crank are each disposed generally at right angles to the other two axes, i. e., as shown in Figure 3, the pivot axis of the guide or hinge 40 is horizontal, the axis of rotation of the blade 22 and carriage 50 is horizontal and at right angles to the pivot axis of the guide, and the axis of rotation of the crank 60 is vertical. However, it is in terms of the association of the components 30, 40, 50 and 60 that the present invention departs from and affords substantial advantages over the prior art. Heretofore, it has been customary to dispose the three axes above defined and the axis of the carriage arm 56 to intersect in a common point. In such relation, when the switch is opened, the blade moves into a vertical position wherein its axis is aligned with the axis of rotation of the crank. In some modifications of the basic design, axes have been slightly offset from common intersection in the closed position of the switch, but in the open position, the axis of the blade is aligned, or only slightly offset from or related at a small angle to the axis of rotation of the crank. Because of this, the switch blade is disposed in, or substantially disposed in, a dead center position wherein the crank can only rotate the blade and loses positive control over arcuate movement of the blade. Because of this, prior art structures have required kicker means or reaction means to move the same off dead center, or have suffered the disadvantage of exceedingly little blade control in switch open position.

According to the present invention, positive control of all movement, and particularly arcuate movement, of the switch blade directly by the crank is attained, and necessity for kicker or reaction means is eliminated. This is accomplished by offsetting the above defined axes in any one of several manners so that in switch open position the axis of the blade is generally parallel to but is offset by a substantial distance from the axis of rotation of the crank, whereby an effective and controlling lever arm is maintained between the crank and blade carriage in all positions of the blade.

In the preferred embodiment of the present invention, the frame 30 is constructed to support the blade guide or hinge 40 on a pivot axis disposed a substantial distance from the axis of rotation of the crank 60 in the direction away from the switch contact 14; the hinge 40 in turn is constructed to support the blade carriage 50 and the blade 22 for rotation about an axis intersecting the pivot axis

of the hinge; and the carriage arm 56 extends from a point forwardly of the hinge pivot axis rearwardly and downwardly beneath the pivot axis of the hinge. This affords a particularly efficient and practical arrangement insuring full control of the blade directly by the crank, and affords the further advantage of imparting a very substantial amount of rotation to the blade while imparting little arcuate movement to the blade in and adjacent switch closed position.

10 Referring now particularly to Figures 5 and 7, the operation of the improved mechanism of the present invention is as follows: As is known in the art, operating mechanism of the general character defined will impart to the switch blade both rotary and arcuate movements, 15 the two movements securing simultaneously, but with one or the other predominating during various stages of operation. As shown in Figure 7, the arcuate movement of the switch blade, plotted against rotary movement of the operating crank, is generally a parabolic function, 20 whereas the rotary movement imparted to the blade is more nearly a straight line function. In Figure 5, the operating crank 60 is shown in switch closed position and in such position the crank or lever arm is disposed approximately 10° over-center with respect to the longitudinal axis of the switch and thus approximately 10° over-center with respect to the vertex of the parabolic curve of arcuate movement. To prevent crank movement beyond this over-travel position, the frame 30 includes a stop portion 36 extending forwardly from the bearing 34 thereof and the crank 60 includes an upstanding tab 68 engaging the stop 36. As the crank is rotated, clockwise as shown in Figure 5, little arcuate movement is imparted to the blade, the blade in fact first tending to dip slightly downwardly, in passing through the vertex of the curve, 30 and then moving upwardly to a slight extent as the crank is moved approximately 20° to the opposite side of center. During this period of crank rotation, substantial rotary movement is imparted to the switch blade 22, the rearward setting of the blade carriage arm 56 resulting in a particularly steep initial portion of the curve of blade rotation as shown in Figure 7, thus to afford a great predominance of rotary movement over arcuate movement in the initial stages of crank rotation. Specifically, before the blade rises 5° it rotates approximately 35°.

45 In the closed position of the switch, the blade 22 is disposed with its flattened contact portion 23 transversely of the legs of the U-shaped contact 14, so that the edges of the portion 23 have high pressure engagement with the contact. As the blade is rotated, the pressure is relieved due to the fact that the transverse dimension of the blade end is effectively decreased in relation to the contact, thus to free the blade end from the contact and accommodate ready removal of the blade end from the contact. During this period, substantially all the power input to the crank, through the insulator stack 18, is utilized to rotate the blade, thus assuring efficient operation. Subsequently, the blade commences slowly to rise and continues to rotate, rotary movement still predominating further to release the pressure of contact engagement, to move the blade clear of the contact, thus to open the switch. Thereafter, as the crank 60 is rotated further in a clockwise direction, the blade rises from the contact relatively rapidly in terms of crank rotation, and arcuate movement of the blade predominates over the rotary movement until the blade attains full open position after about 120° crank rotation. Crank rotation through this angle effects approximately 80° blade rotation and movement of the blade through an arc of approximately 90°.

70 In moving the switch blade from closed to open position, the distance between the crank arm 66 and the blade carriage becomes greater, the crank and carriage are rotated relatively, and the angular relation of the carriage arm to the crank changes, all of which movements are accommodated by the elongate extension 57 of the carriage and the spherical bearing 67 of the crank. When

the switch blade attains its open position, the axis of the blade, and thus the axis of rotation of the carriage 50, is disposed generally parallel to, but is offset a substantial distance rearwardly from the axis of rotation of the crank 60 and stack 18. Due to this relationship, the crank has an effective lever arm to the carriage and thus exerts full control over the blade to commence return movement of the blade when desired upon reverse rotation of the crank. In all positions of the blade, the crank exerts full influence or control over the same.

To close the switch, the crank 60 is rotated in a counterclockwise direction as shown in Figure 5, whereupon the crank, through the arm 56 and carriage 50, positively drives the blade into the contact. Specifically, the blade is forced to complete both the arcuate and rotary movements thereof before the crank is stopped in closed position by virtue of the tab 68 engaging the stop 36. As the blade is moved arcuately into the contact, the flattened blade end 23 is inclined to the legs of the contact 14 to facilitate ready entry of the blade end, whereupon the blade rotates into increasingly greater pressure engagement with the contact to wipe the contact portions clean. As the blade end is forced into deeply seating position in the contact, the blade is rotated a very substantial extent in relation to arcuate movement of the blade, to complete the high pressure engagement with the contact and to dispose the flattened blade end 23 transversely of the contact as the crank is returned to the position shown in Figure 5.

As previously pointed out, the blade 22 at its opposite end extends rearwardly from the carriage 50, and this portion of the blade is moved in an arc and rotated in the confines of the frame 30 during the above described movements. To effect substantial direct connection between the switch blade 22 and the terminal pad 32, to minimize transfer or exchange points, a contact 70 is provided within the frame 30 for cooperation with the tail end of the blade. Specifically, as shown in Figures 2 and 3, the angular portions of the arms 33 of the frame each have bolted thereto a contact leaf 71. The leaves 71 are thus opposed and are bolted to the arms 33 at their lower ends and extend upwardly to the straight portion of the frame arms to engage opposite sides of the blade end in switch closed position. To bias the contact leaves 71 into engagement with the blade, the frame arms 33 are each formed with a socket therein adapted for the reception of a coiled spring 72 to bear on the outer end of the respective contact leaf. To insure good contact, the leaves 71 are preferably provided with a silver inlay 73 at the end portions thereof, and the switch blade may include opposed ribs or be flattened to attain the same high pressure engagement with the contacts as described hereinbefore. However, I have found that adequate contact engagement may be attained at the base end of the switch blade merely with a tubular blade form. The contact leaves 71, being mounted on the frame 30, are thus directly connected to the terminal pad 32. To complete the electrical circuit arrangement, the switch includes a sheet metal slip ring member 75 bolted to the blade hinge 40 and having one end engaging a stub axle 35 and the other end formed arcuately to bear on the flange 54 of the blade carriage 50 to afford, for protective purposes, a connection between the terminal 32 and the switch blade after the blade has cleared the contact 70.

The switch construction above described, as shown in Figures 2 to 5, is particularly adapted for the lower capacities, including only one pair of contact leaves 71, a fairly short rearward blade end portion and being set fairly close to the tops of the insulator stacks 12, 16 and 18. In higher capacities, more contact area is required. For this purpose, as shown in Figure 6, the frame 30 of the operating mechanism of the invention is modified to carry two pairs of contact leaves 71, and to accommodate

the greater length of blade end necessary to engage the contacts 71, the frame is increased in height so that the blade end may swing freely down and over the edge portions of the insulator stack 18 in switch open position.

5 The blade carriage 50 and hinge 40 need not be appreciably changed, except to accommodate a blade of larger diameter, and to operate the resultant assembly a modified crank 60, of greater height than the previously described crank, is necessary. In other respects, the structure and operation of the high capacity switch is the same as that of the lower capacity switch.

In view of the foregoing, it is to be appreciated that the present invention provides an improved disconnecting switch of particularly economical and efficient construction affording marked advantages in the art. Further, the invention provides an improved operating mechanism for switches of the character referred to affording full blade control in all positions of the blade and imparting improved operational characteristics to the blade.

15 While I have described what I regard to be preferred embodiments of my invention, it will be apparent that various changes, rearrangements and modifications may be made therein without departing from the scope of the invention, as defined by the appended claims.

20 I claim:

1. In a disconnecting switch having a switch blade rotatable about its own axis and arcuately movable between two end positions, operating mechanism for the blade comprising a frame, a blade hinge pivotally mounted on the frame, a blade carriage rotatably mounted on the hinge, and a rotatable operating crank operatively connected to the carriage, the pivot axis of said hinge and the axes of rotation of said carriage and said crank in one end position of the blade each being disposed substantially at right angles to the other two axes, one of said axes of rotation substantially intersecting the pivot axis of said hinge and the other being substantially offset from said pivot axis; said carriage including a rigid angular extension and said crank including a complementary extension, said extensions being operatively connected for relative sliding, rotating and swiveling movement.

2. In a disconnecting switch having a switch blade rotatable about its own axis and arcuately movable between two end positions, operating mechanism for the blade comprising a frame, a blade hinge pivotally mounted on the frame, a blade carriage rotatably mounted on the hinge, and a rotatable operating crank operatively connected to the carriage, the pivot axis of said hinge and the axes of rotation of said carriage and said crank in one end position of the blade each being disposed substantially at right angles to the other two axes, at least one of said axes of rotation being offset a significant distance from the pivot axis of said hinge whereby said axes of rotation in the other end position of the blade are disposed generally parallel and are spaced apart a substantial distance, said carriage including a rigid angular extension and said crank including a complementary extension, said extensions being operatively connected for relative sliding, rotating and swiveling movement.

3. In a disconnecting switch having a pair of spaced stationary contacts and a switch blade rotatable about its own axis and arcuately movable between an open position disengaged from the contacts and a closed position wherein the blade engages said contacts at its opposite ends, operating mechanism for the blade comprising a frame, a blade hinge pivotally mounted on the frame intermediate the stationary contacts, a blade carriage rotatably mounted on the hinge, the blade being fixed to and extending through said carriage to the opposite sides thereof to expose the opposite ends of the blade for engagement with the contacts, a rotatable operating crank operatively connected to said carriage, the pivot axis of said hinge and the axes of rotation of said carriage and said crank in the closed position of the blade each being disposed substantially at right angles to the other two

axes, at least one of the said axes of rotation being offset a significant distance from the pivot axis of said hinge to dispose said axes of rotation, in the open position of the blade, in generally parallel but significantly offset relation, said carriage including a rigid angular extension and said crank including a complementary extension, and means operatively connecting said extensions for relative sliding, rotating and swiveling movement, whereby said crank is adapted to rotate and move the blade between its open and closed positions and maintains full control over the blade in all positions thereof.

4. In a disconnecting switch having a switch blade rotatable about its own axis and arcuately movable between two end positions, operating mechanism for the blade comprising a stationary frame, a blade hinge pivotally mounted on the frame, a blade carriage rotatably mounted on the hinge coaxially of the switch blade, the blade being secured to said carriage, a rotatable operating crank, and pivot means operatively connecting said crank and said carriage, the pivot axis of said hinge and the axes of rotation of said carriage and said crank in one end position of the blade each being disposed substantially at right angles to the other two axes, the axis of rotation of said carriage substantially intersecting the pivot axis of said hinge and the axis of rotation of said crank being substantially offset from said pivot axis.

5. In a disconnecting switch having a stationary contact and a switch blade rotatable about its own axis into and out of high pressure engagement with the contact and arcuately movable into and out of switch closed position in the contact, operating mechanism for the blade comprising a stationary frame spaced from the contact, a blade hinge pivotally mounted on said frame, a blade carriage rotatably mounted on said hinge coaxially of the blade, the blade being fixed to said carriage, the axis of rotation of said carriage substantially intersecting the pivot axis of said hinge at substantially a right angle thereto, a rotatable operating crank disposed in spaced relation to said hinge and said carriage, the axis of rotation of said crank in the closed position of the switch extending generally at a right

angle to both the pivot axis of said hinge and the axis of rotation of said carriage and being spaced substantially from said pivot axis in the direction of the stationary contact, and pivot means operatively connecting

5 said crank and said carriage, said pivot means in the closed position of the switch extending between said crank and said carriage to the side of the axis of rotation of said crank opposite the stationary contact and accommodating variation in the distance between said carriage and said crank during movement of the switch blade.

6. In a disconnecting switch having a stationary contact and a switch blade rotatable about its own axis into and out of high pressure engagement with the contact and arcuately movable into and out of switch closed position

15 in the contact, operating mechanism for the blade comprising a stationary frame spaced from the contact, a blade hinge pivotally mounted on said frame, a blade carriage rotatably mounted on said hinge coaxially of the blade, the blade being fixed to said carriage, the axis

20 of rotation of said carriage substantially intersecting the pivot axis of said hinge at substantially a right angle thereto, a rotatable operating crank disposed in spaced relation to said hinge and said carriage, the axis of rotation of said crank in the closed position of the

25 switch extending generally at a right angle to both the pivot axis of said hinge and the axis of rotation of said carriage and being spaced substantially from said pivot axis in the direction of the stationary contact, and an arm extending angularly from said carriage and slidably and rotatably received in the outer end portion of said crank, said arm in the closed position of the switch extending from a portion of said carriage to the contact side of the pivot axis of said hinge to the opposite side of said pivot axis for connection to said crank.
